David Atkin, London, England, assignor to The Cannon Rubber Manufacturers Limited, London, England

Application July 18, 1950, Serial No. 11,250
In Great Britain May 23, 1950

Term of patent 7 years

(Cl. D83—1)

To all whom it may concern:

Be it known that I, David Atkin, a citizen of England, residing at London, England, have invented a new, original, and ornamental Design for Hot-Water Bottle, of which the following is a specification, reference being had to the accompanying drawing, forming a part hereof.

Fig. 1 is a front elevational view of a hot-water bottle embodying my new design;

Fig. 2 is a top view; and

Fig. 3 is a rear perspective view partly seen from underneath.

I claim:

The ornamental design for a hot-water bottle, as shown.

DAVID ATKIN.
